United States Patent Office.

JOHN DUNDAS, OF NEW YORK, N. Y.

Design No. 2,728, dated August 6, 1867.

DESIGN FOR AN ORNAMENTAL STAR.

The Schedule referred to in these Letters Patent and making part of the same.

TO ALL WHOM IT MAY CONCERN:

Be it known that I, JOHN DUNDAS, of the city and State of New York, have invented, made, or produced a new and original Design for an Ornamental Star; and I do hereby declare the following to be a correct description of the same, reference being had to the annexed drawing, making part of this specification, wherein—

Figure 1 is a photographic view of the said ornamental star, and

Figure 2 is a vertical section of the same.

The points of said star are each formed with converging sides, with bead-work ornaments around the edges, formed by small prismatic recesses, as at *a*. The point *b* is recessed, and its surface a series of planes, giving the appearance of silvered glass prisms, the surface being polished. The body of the star itself is formed as a concave prismatic reflector, *c*, in the middle of which is a small cylinder, *d*, the surface of which may be covered with tinsel, and the end of this cylinder is ornamented by a cluster or flower-shaped design, *e*, formed of a series of small prismatic recesses. The points of the star formed in this manner, and the concave prismatic centre, all having plane reflecting surfaces, form a handsome glistening ornament, that may be used for upholstery or other decorations.

What I claim, and desire to secure by Letters Patent, is—

The design for the points of an ornamental star, substantially as shown and described.

In witness whereof I have hereunto set my signature this 27th day of June, 1867.

JOHN DUNDAS.
